United States Patent Office

Des. 189,679
Patented Jan. 31, 1961

189,679

TUMBLER OR SIMILAR ARTICLE

Rudolph A. Sampson, Cleveland, Ohio, assignor of one-third to Webb C. Jennings, Rocky River, and one-third to Ira T. Swartwood, Lakewood, Ohio

Filed Feb. 25, 1960, Ser. No. 59,514

Term of patent 14 years

(Cl. D36—8)

The figure is a perspective view of a tumbler or similar article embodying my new design. The side not shown is the same as the side shown.

I claim:

An ornamental design for a tumbler or similar article, substantially as shown and described.
